(57) **CLAIM**

I claim the ornamental design for a vehicle front spoiler, as shown and described.

DESCRIPTION

FIG. 1 is a right front perspective view of a vehicle front spoiler showing the claimed design;

FIG. 2 is a right rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The low contrast or “ghost” areas of the drawings depict portions of the vehicle front spoiler that form no part of the claim.

The broken lines enclosing low contrast or “ghost” areas of the drawing depict portions of the vehicle front spoiler that form no part of the claimed design.
